UNITED STATES PATENT OFFICE

114,209

DESIGN FOR A COMBINED BOTTLE STOPPER AND LIQUID POURER

Chester F. Eklund, New York, N. Y., assignor to
Daniel M. Fox, New York, N. Y.

Application July 7, 1938, Serial No. 78,328

Term of patent 14 years

To all whom it may concern:

Be it known that I, Chester F. Eklund, a citizen of the United States and a resident of the city of New York, in the county of New York and State of New York, have invented a new, original, and ornamental Design for a Combined Bottle Stopper and Liquid Pourer, of which the following is a specification, reference being had to the accompanying drawing, forming part thereof, in which:

Figure 1 is a side view of a combined bottle stopper and liquid pourer embodying my new design.

Fig. 2 shows the bottle stopper and liquid pourer in open position.

Fig. 3 is a front view thereof.

My design is characterized by a combined bottle stopper and pourer of the configuration shown, the head and upper beak portion being in one piece and movable with respect to the lower portion of the beak to form a pouring opening and the head portion being tiltable with respect to the body portion of the stopper about an axis intermediate the extremities of the head.

I claim:

The ornamental design for a combined bottle stopper and liquid pourer, substantially as shown and described.

CHESTER F. EKLUND.
